UNITED STATES PATENT OFFICE.

ALPHONSE H. KURSHEEDT, OF NEW YORK, N. Y.

BEAD-SEWING MACHINE.

Application filed June 14, 1921. Serial No. 477,357.

To all whom it may concern:

Be it known that I, ALPHONSE H. KURSHEEDT, a citizen of the United States, residing in the city, county, and State of New York, have invented certain new and useful Improvements in Bead-Sewing Machines, of which the following is a specification.

My invention relates to sewing machines which are adapted for use in attaching beads or similar ornamental elements to a fabric; and my improvements are directed particularly to the means for feeding or propelling the beads one by one down to their proper positions upon the fabric, after each bead 10 has been separated from those above it by the bead separating mechanism.

Heretofore, in the art, beads have been strung loosely upon a thread, which thread 20 has been secured to the fabric by suitable stitching mechanism, the beads sliding down along the thread, under the influence of gravity until they reach a separator, which passes them one by one and allows them to slide on down the thread to the point where 25 they are to be fastened to the fabric. This movement of the beads below the separator is dependent upon the weight of each bead being sufficient to cause it to slide down the thread. Irregularities of size in the thread, 30 or loose fibres projecting from it, or other elements connected with the thread may tend to arrest the descent of a bead, or, if the perforation through the bead is of an abnormal form, the bead may not slide down the 35 thread with the precision and certainty which are essential for accurate work.

It is the object of my invention to provide means for positively pushing or propelling the bead down the thread, below the separator, to the fabric, so that it will assuredly reach its proper position promptly and accurately, as I will now proceed to point out and explain, referring, in so doing, to the accompanying drawings in which Fig. 1 is 40 an elevation showing the principal bead feeding and stitching elements of a bead-sewing machine, to which my improved auxiliary feed mechanism is attached; Fig. 2 is a partial end view, looking to the left on Fig. 45 1; Fig. 3 is a detail, on an enlarged scale, of the bead separating mechanism and of the part of my auxiliary feed mechanism associated therewith, the latter being partly in

section; and Fig. 4 is a cross sectional view of the same, taken on the line 4—4 of Fig. 3, 55 looking down, the bead guide and follower however being in their initial positions.

In all the figures the same parts are designated by corresponding reference numerals.

The base 1 of the machine carries a standard 2, provided with a bracket arm 3. In suitable bearings in the standard and arm is mounted the driving shaft 4, which, by means of a pin 5 raises and lowers a slide 6, an arm on which carries a nut 7 which is 60 threaded on a tube 8 mounted in bearings in the head of the machine, so that as the nut 7 is raised and lowered the tube will be turned first in one direction and then in the other. 70

To the lower end of the tube 8 are attached the bead guide 9 and bead follower 10, which travel forward and back with the tube 8 as it is moved first in one direction and then in the other, the follower being 75 held to duty by the guide arm 11 carried by the head of the machine.

The bead separator 12 is also carried by the head of the machine; and, in operation, the bead guide 9 and follower 10 move 80 around it, forward and back, with each forward movement causing one bead to pass below the edge 13 of the separator, from which point it may slide down the thread to the fabric. 85

Through suitable gears 14, 15, shaft 16, gears 17, 18 and shaft 19, the needle slide 20 is raised and lowered in the usual manner to cause the needle to perform its stitch making movements. 90

These elements of the machine are shown as illustrating a type of mechanism, known in the art, with which my improvements may be combined, and not as embracing novel matter invented by me. 95

In the face of the gear 18 I secure a wrist pin 21, on which is pivoted a piston rod 22, carrying a piston head 23, provided with a suitable flap valve 24 and sliding in the cylinder 25, which is secured by suitable means, 100 as 26, to the standard 2.

A ball valve 27 controls the outlets from the piston cylinder, and from it a tube 28 is carried over to the head of the machine, and down to an annular terminal 29, positioned 105 around and slightly above the separator 12.

This terminal is provided with a series of openings 30, 30, directed inwardly and downwardly toward a point below the bead separator; the arrangement being such that when air is forced into the tube 28, by the action of the piston 23, it will escape through the openings 30, 30, in inwardly and downwardly converging jets so as to drive down before it any loose or partially free article, such as a bead strung upon the bead thread, which will be urged down by the air jets until it reaches the fabric where the thread is attached to it.

As the air pump is adjusted, as shown, to make one upward stroke with each stitch movement of the machine, it follows that the air jets may be made to operate during the forward or bead feeding movement of the separator, the bead, in the type of machine which I have illustrated, being free to drop after the bead guide and follower have made about one quarter of their forward movement, at which point the force of the compressed air will be substantial and will continue to increase as the separating elements move forward. The down stroke of the piston 23 is preferably adjusted to correspond with the return movement of the separating elements.

For clearness I have omitted the fabric feeding mechanism and the means for changing the direction of feed.

But, as those skilled in the art understand, when the direction of feed is changed, the position of the bead separator must also be correspondingly changed by moving the separator around the needle point, the feeder and follower elements being also moved so as to retain their normal positions relative to the separator. Consequently if the air tube terminal is stationary, as I have illustrated it as being, it is desirable to have it provided with a plurality of air jet orifices, so that in whatever position the separator may be set there will always be jet openings pointing downward past the position of the separator beneath which the beads descend.

I wish it to be understood that the means I have illustrated for carrying out my invention are to be considered as typical means and not as showing the sole means for securing the ends in view. For mechanical equivalents or the like may be employed to give the same result, without departing from the spirit of my invention as claimed. For instance a continuous instead of an intermittent current of air may be used if desired.

Having thus described my invention what

I claim and desire to secure by Letters Patent of the United States is —

1. The combination, with the bead-separating mechanism of a bead sewing machine, of feeding means adapted to operate on the beads below their final point of separation.

2. The combination, with the bead-separating mechanism of a bead sewing machine, of feeding means adapted to operate on the several beads successively below their final point of separation.

3. The combination, with a bead-separating mechanism of a bead sewing machine, of feeding means adapted to operate on the beads below their final point of separation to propel them toward the fabric.

4. The combination, with a bead-separating mechanism of a bead sewing machine, of pneumatic feeding means adapted to operate on the beads below their final point of separation.

5. The combination, with a bead-separating mechanism of a bead sewing machine, of pneumatic feeding means adapted to cause an air current to operate on the beads below their point of separation.

6. The combination, with a bead-separating mechanism of a bead sewing machine, of pneumatic feeding means adapted to cause a plurality of air currents to operate on the beads below their point of separation.

7. The combination, with means in a bead sewing machine embodying a bead separator, of means for producing a current of air, means for conducting it to a point near the bead separator, and means for discharging it downwardly past the separator.

8. The combination, with means in a bead sewing machine embodying a bead separator, of means for producing a current of air, means for conducting it to a point near the bead separator, and means for discharging it in converging jets downwardly past the separator.

9. The combination, with means in a bead sewing machine embodying a bead separator, of means for producing a current of air, means for conducting it to a point near the bead separator, and means for discharging it in converging jets past the separator toward a selected bead position.

10. The combination, with the bead-separating mechanism of a bead sewing machine, of feeding means adapted to operate intermittently on the beads below their point of final separation.

ALPHONSE H. KURSHEEDT.
